UNITED STATES PATENT OFFICE

ROBERT HENRY COLLEN, OF EAST HAM, ENGLAND, ASSIGNOR OF ONE-HALF TO JOHN BROADWOOD & SONS LIMITED, OF LONDON, ENGLAND

PIANOFORTE

Application filed November 9, 1926, Serial No. 147,272, and in Great Britain November 26, 1925.

This invention has for its object to provide an improved construction of pianoforte of the upright, or cottage, type whereby it can be more economically, easily and efficiently 5 manufactured, or constructed, than hitherto, and wherein liability of injury to parts during its manufacture, or construction, is reduced to a minimum, and mainly consists in making the enclosing case, or cabinet, of the 10 instrument as a single and independent unit (hereinafter referred to as the case-unit) and in making and assembling the various parts that constitute the mechanism proper of the said instrument, that is, the iron frame, sound 15 board strings, action, keys and other associate parts, as another separate and independent unit (hereinafter referred to as the playing-unit) so that to complete the instrument it is only necessary to place the playing-unit in 20 the case-unit and to secure the said units together preferably by means such that, when required, they may be easily and quickly separated the one from the other and again be united, or such that one of the said units may 25 be changed.

We will describe an example of a pianoforte constructed in accordance with this invention with reference to the accompanying drawings in which Figure 1 is a section 30 through the case of the pianoforte, Figure 2 is an elevation of the metal pianoforte frame, attached to a bottom board, Figure 3 is a section on the lines *a*, *a*, of Figure 2, the said section also shewing the sound board and the 35 arms for supporting the playing unit, Figure 4 is a perspective view of the sound board as a separate unit, Figure 5 is a perspective view of part of the front of the metal frame shewing the bottom board and key board attached 40 thereto and Figure 6 is a perspective view of part of the casing in position to be attached to the parts shewn in Figure 5.

Referring to Figures 2 and 3, the metal frame *A* shewn is made of stronger section 45 than usual so that it can take the full tension of the strings whereby the heavy timber back provided in pianofortes as hitherto constructed is dispensed with. The actual stringing portion of the frame may be of any suitable, or known, construction. On the rear

side of the frame is an endless web *B* which constitutes a flange within which the sound board closely fits, a slightly raised, or thickened, portion *C* within and adjoining the said web, or flange, constituting a seating for the sound board. Instead of the web *B* the frame 55 *A* may be cast with bosses (not shewn) there being as many as are required for the purpose of bolting the sound-board through each of the corner joints, to the frame.

The sound board (Figure 4) consists of a board *D* having glued, or otherwise secured to the edges of its rear face, the sound board rails *E* and the diagonal bars *F*, all of which may be as usual, but preferably the said sound 60 board rails *E* are wider and deeper than usual. The sound board is made the same outside shape as the shape of the web *B* into which it fits and is secured to the frame *A* by bolts, or screws, passed through the holes *H* 65 and *I* in the sound board and frame respectively. The wrest-plank *J* for the tuning pins is secured in the usual position to the rear side of the iron frame *A* by bolts passing through holes *I*² in the known, or any suitable, manner. Secured to, or formed in one with, the said iron frame *A* are suitably shaped feet *L* for supporting the said frame and by which it can be securely bolted to a board *M* of substantial thickness which constitutes the bottom board of the instrument when the playing-unit is in position in the case-unit, and therefore the length of the said board will be such as to properly fit between the main end, or vertical, members of the said 80 case-unit. Projecting from the front of the said iron frame at, or about, midway of its height and at a suitable distance from each end thereof are arms *R*, adapted to support the key bottom board *Q*, the keys and action 85 mechanism, the latter, which may be as usual, not being shewn. The said supporting arms *R* may be formed in one with the said iron frame *A* or be secured thereto in any suitable manner. In Figure 5 bosses *O* are cast on in two pairs, one pair situated towards the treble end and one pair towards the bass end, one boss being at a distance beneath its corresponding boss for the purpose of bolting to each pair an angle iron bracket *P*, to support 90

100

the key bottom board Q. The said key bottom board may be a solid board, or a built up framed board, and it may be secured to the supporting arms, or its equivalent, by screws or other equivalent means.

5 Presuming the wrest-plank J to have been bored for the reception of the tuning pins, the said pins to have been fitted therein, the iron frame A strung in the usual manner and the hereinbefore mentioned parts to have been secured as described, the so far constructed playing unit is now in condition to have mounted thereon the keys, action and pedal mechanism and when these parts have 10 been properly fitted finished and regulated, and the strings tuned the whole constitutes 15 a complete playable unit but without the enclosing casing which is constructed as an entirely separate unit as hereinafter described.

20 The fitting of the keys, action and pedal mechanism and the finishing and regulating is the same as in ordinary pianoforte construction and therefore requires no description and is not shewn in the drawings, but 25 it will be obvious that such fitting, finishing and regulating can be more easily, quickly and efficiently effected when free from the casing, and moreover the liability of injury 30 to the said casing, which in the known manner of construction had hitherto been present, is in the construction according to this invention entirely eliminated.

35 For convenience in conveying the playing unit, during the various stages of its construction, from shop to shop, in a factory, the bottom board to which the iron frame is secured may be removably secured to a trolley.

40 For the sake of convenience, the unit heretofore referred to as the playing-unit may be termed the main resonant parts of the piano and consist of the string frame A and sounding board D which has associated therewith 45 as a unitary structure the key bottom board. It is, of course, understood that the piano case itself is likewise resonant but the case is intended to be excluded from the term "main resonant parts".

50 The case unit is preferably constructed as shewn in Figures 1 and 6. To the inner side of each of the main end, or vertical, members 1 are glued and screwed to the cheek-members 2 and the toe-members 3. The cheek-members 55 are extended downwards beyond the usual level of the key bottom and the forward portion of each of the said cheek-members is supported by a leg 4 interposed between and secured to the under-side of 60 the said forward portion of the said cheek-member and the upper side of the forward portion of the said toe-member. Each of the cheek-members is preferably formed from a solid piece of wood of substantial 65 thickness for strength and its rear portion

2^a projects to any desired extent inwardly of the main end, or vertical, members to which it is secured. Each of the toe-members 3 is also preferably formed from a solid piece of wood and projects rearwardly to 70

practically the rear end of the said main end, or vertical member 1 to which it is secured and each has a portion at its rear cut away from its underside to permit of the bottom board M of the playing unit sliding thereunder. The frame into which the bottom door fits consists of a bottom rail 5, commonly known in the art as the "plinth", a top rail 6, commonly known in the art as the "fast-rail", and end rails 7 commonly known in the art as "door-posts", or "pilasters", each being morticed, tenoned and secured the one to the other and to the main end, or vertical, members and to the top members in such manner as to constitute a tie between the lower part of the said main end, or vertical, members and also constitute a substantial intermediate bracing for the lower portion of the case. The fast-rail has 80

suitable portions cut away at its upper part to permit of the passage of the arms, or the equivalent, on the iron-frame of the playing-unit when the said playing-unit and the case-unit are assembled, the upper part of the door-posts 7, or pilasters, have portions cut away to clear the cheek-members 2 and openings are cut in the plinth for the insertion of the pedal feet. The bottom-door 8 is adapted to fit in the aforesaid frame and to be removably secured therein by means of 90 fillets, dowels and turn-buttons in the known, or any suitable, way.

95 For rigidity of the upper portion of the case, in addition to the back-half 9 of the top horizontal member a sub-top 10 is provided which is dovetailed, or suitably fixed to the two end members 1, the upper surface to be flush with the top of the said end members and in a position directly underneath the top member 9.

100 For the purpose of making contact and fixing between the top portion of the case and the flanges 3 of the blank portion of the iron frame A, the two end vertical members are provided on their inside faces with a thickened portion 18 extending from the top of the said ends to the top of the cheek-member 2, of a thickness corresponding to the width of the said flanges S of the iron frame. Hinged to the said back-half 9 of the top, or horizontal member, is the front-half 11 of the said member which may be as usual. The forward, or front, ends of the said cheek-members 2 are rigidly connected by a rail 12 of the same or approximately the same, thickness as the key-bottom board on the playing unit and against which the said board butts when the playing-unit is in position in the case, the said rail also constitutes the member to which the lock-rail 115

110

115

120

125

130

13 is secured. Secured to the inner sides of the cheek-members are strips 14 which act to properly position the removable back-hollow 15 to which is hinged the fall 16 which 5 closes down onto the aforesaid lock-rail 13.

The top door 17 butts against the front edges of the main vertical, or end, members and may be removably secured to the case by any known, or suitable, means.

10 The case-unit having been completely made and assembled as aforesaid is suitably polished and provided with two front castors fixed in the usual position to the forward part of the toe-members and it is then ready

15 to receive and have secured therein the playing-unit hereinbefore described. This is effected by sliding the case-unit onto the front of the playing-unit until the following parts engage, or contact, one with the other (see 20 Figures 5 and 6).

The rear portion of the toe-members 3 being under-cut to the depth of the bottom-board M of the playing-unit permits the said toe-members to ride over the said bottom-board until the rear side of the 25

plinth butts against the said bottom-board; the key-bottom board Q will then be butting against the front rail 12 beneath the lock-rail 13 and the flanges S of the iron frame will be butting up to the inside edges of the thickened up insides 18 of the ends 1, and upon the pedal feet being passed through the openings formed in the plinth and connected to the levers which they respectively actuate, the two units are completely assembled and 35

are ready to be removably secured together. This may be effected by any suitable means, for example, the lower portions of the units may be secured by screws, or bolts, passing through holes 19 in the toe-members of the 40

case-unit and the bottom board of the playing-unit, the key-bottom board Q may be secured to the inside faces of the cheek-members 2 by angle brackets or wood fillets screwed respectively into the cheek members 45

and into the key-bottom board and for securing the upper portions bolts may be used, passing through a clear hole T at each end in the plank J and flanges S of the frame, through also a clear hole U in the thickness 50

18 of the inside end pieces, screwing up ultimately in a threaded metal inset 19 let into the extra thickness 18 of the inside ends 1. If necessary, distance piece screws may be 55 inserted in the contact part of the inside ends, one above and one below, the said bolt to counteract any possible distortion of the units and to facilitate the contact of the case-unit with the playing-unit at these points.

60 This manner of connecting up the units at their top, bottom and mid parts ensures a rigid connection which is efficient and simple and permits of the said units being easily disconnected when desired for effecting repairs, 65 or renewals, and moreover either of the said

units may be removed and replaced by another should at anytime it be desired to do so.

It will be understood that the invention is not limited to the particular construction of the parts described.

I claim:—

1. An upright pianoforte comprising a case-unit, in combination with a unit formed separately from said case-unit constituting the main resonant parts and a key-bottom board and means for removably securing said second mentioned unit to said case-unit.

2. An upright pianoforte comprising a case-unit, vertical end members forming a part of said case-unit, and thickened upper portions on said vertical end members, in combination with a unit formed separately from said case-unit constituting the main resonant parts and a key-bottom board and means for removably securing the top of the 75

pianoforte frame to the thickened upper portions of the vertical end members, said case-unit and said second mentioned unit being thereby adapted for ready attachment and detachment.

3. An upright pianoforte comprising a case-unit, vertical end members forming a part of said case-unit, thickened upper portions on said vertical end members and toe members attached to the lower portions of

95 said vertical end members, in combination with a unit formed separately from said case-unit constituting the main resonant parts and a key-bottom board, a bottom rail upon which said second mentioned unit is 100 mounted, means for removably securing the top of the pianoforte frame to the thickened upper portions of the vertical end members, and means for removably securing the bottom rail to the toe members, said case-unit and 105 said second mentioned unit being adapted for ready attachment and detachment, substantially as described.

In testimony whereof I have signed my name to this specification.

ROBERT HENRY COLLEN.
